COIN-CONTROLLED CALLING-CARD BOX

Application filed November 5, 1928. Serial No. 317,165.

This invention relates to a new and useful device in the nature of a coin controlled calling card box. The object of the invention is to provide a box or receptacle adapted to hold a plurality of calling cards and having a coin controlled lock so as to prevent the loss of the calling cards placed therein. It is readily understood that in event a person called on is absent that the caller would not hesitate to spend a coin, preferably five cents to deposit his calling card in a safe place.

A further object of the invention is to provide a device of the class described of novel construction and arrangement of parts hereinafter more fully described, claimed and illustrated in the accompanying drawing.

Fig. 1 is a perspective view of our improved device.

Fig. 2 is a front elevational view thereof showing the door in an open position.

Fig. 3 is an enlarged inside view of the door showing the coin receptacle in section.

Fig. 4 is a side elevational view of the door.

Fig. 5 is a vertical sectional view of the box proper showing in particular the pockets provided to receive the calling cards.

Fig. 6 is a front elevational view of the box proper showing the calling card pockets and locking mechanism.

Fig. 7 is a side elevational view of the lock proper.

Fig. 8 is a side elevational view of the advance mechanism as embodied in our improved device.

As here embodied our improved device comprises a receptacle 10, of box-like construction, open at the front thereof. A door 11, adapted to enclose or cover the above mentioned opening, is hinged in the conventional manner, as at 12 and 13 to one side of the receptacle 10. The door 11 has formed therein in proximity to the upper edge thereof an aperture 14, adapted to receive a coin preferably a five cent piece. A plate 15 is secured

to the door 11 in proximity to the aperture 14 and has affixed thereto any desired instructions pertaining to the inserting of the said coin, as clearly shown in Fig. 1.

A coin guide 16, consisting of a strip of metal suitably formed or bent so as to pro-

vide a vertically disposed opening 17 is secured to the inner side of the door 11, and extends over the aperture 14, downwardly therefrom in proximity to the lower or bottom edge of the door.

A coin operating lever 18 is pivotally attached as at 19 to the extended element of a bracket 20 secured to the inner side of the door 11. This lever 18 is provided with a free extremity 21 which extends into the opening 17 through a slot 22 provided for this purpose. A counterweight 23 is slidably mounted on the opposite free extremity, and is adjustably secured thereto by a threaded member 24 preferably a set screw or the like. A locking pin 26 is pivotally attached at its upper extremity, as at 29 to the lever 18 intermediate the bracket 20 and the free extremity 25 of the said lever. This pin 26 is provided with a free extended extremity adapted to normally engage in a slot 30 formed intermediate in the locking bar 31.

The locking bar 31 is slidably mounted on a bracket 32 secured to the inner side of the door 11, and in the coin guide 16, which has formed therein opening adapted to receive the said locking bar. A tension spring 33 is secured to the locking bar 31 and to the inner side of the door 11 so as to normally hold the extremity 34 in a somewhat extended position, directly at the rear of the cleat 35 secured to the receptacle 10 adjacent to the side of the door 11 opposite the hinges 12 and 13, so as to normally hold the door 11 in a closed, locked position. A tension spring 27 is secured to the door 11 and to the receptacle 10 for the purpose of closing the door 11.

A knob 36 is positioned outside the door 11 and is secured to a pin 37 rotatively mounted in the door and in a bracket 38 secured to the inner side of the door 11. This pin 37 has secured thereto a pinion 39 engaging with suitable gear teeth 40 formed in the lower edge of the locking bar 31. The knob 36 has affixed thereto any desired instructions as clearly shown in Fig. 1 for the manipulation or turning of the said knob. An arrow 41 is affixed to the door 11 in proximity to the knob 36 denoting the correct direction to turn the knob 36.

It is obvious that the above described construction is such as will permit a coin, preferably a five cent piece when inserted in the aperture 14 to fall downwardly through the opening 17 provided in the coin guide 16 and strike the free extremity 21 of the lever 18, as designated by the reference numeral 41. The coin 41 will partially rotate or pivot the lever 18 as designated by the reference numeral 42, the said coin then residing or resting on the locking bar 31, as designated by the reference numeral 43. The partial rotation of the lever 18 will disengage the locking pin 26 permitting the knob 36 to be rotated so as to disengage the extremity 34 from the cleat 35, for the purpose of opening the door 11.

The movement of the locking bar 31 will permit the coin to fall through the opening 20 44 formed in the locking bar and through an opening 46 formed in the bottom of the receiver 10 into the coin receiver 45, and will simultaneously release the lever 18.

The coin receiver 45, is of tray or drawer-like construction slidably mounted in a suitable container 47 secured to the bottom of the receptacle 10. The coin receiver 45 is provided with a suitable lock 48, as a means of preventing theft of the coins deposited therein. A conventional counter 49 is secured to the coin receiver 45 and is provided with the usual operating lever 50 positioned directly below the opening 46 which the coin strikes for the purpose of designating the total number of coins in the coin receiver 45. An opening 51 is provided in the container 47 for the purpose of permitting the numerals on the counter 49 to be visible at all times.

The rear member 10' or back of the receptacle 10 has secured thereto a plurality of plate members 55 substantially of rectangular shape positioned in a vertical row. These plate members 55 are provided with lower lug elements 56 having formed therein apertures adapted to rotatively receive the pins 57. The pins 57 are carried in the lower portions of the pockets 58, as a means of hinging the pockets 58 to the plate members 55. These pockets 58 are of hollow rectangular construction, so as to provide cavities 59 adapted to receive a calling card. A flexible member 60, cord, string, chain, or the like is secured to the plate members 55 and to the pockets 59 as a means of normally holding the pockets 59 in an outwardly inclined or open position so as to permit a calling card to be placed therein. The pockets 59 are provided with suitable locks 61 of the self-locking type, adapted to automatically lock the pockets in a closed position when the said pockets are closed.

The plate members 55 have affixed thereto any suitable instructions as at 62 relative to the inserting of the calling cards. Suitable

instructions 63 are affixed to the pockets 58 relative to the closing of the said pockets.

The pins 57 have secured thereto at one extremity thereof advance members 64 provided with extended elements 65, for the purpose as hereinafter set forth. A bar 66 is slidably mounted in brackets 67 and 68 secured to the rear member 10' and has formed therein serrations 69 or teeth adapted to be engaged by the extended extremities 65 of the advancement members 64 when the above mentioned pockets 59 are closed as a means of advancing or lowering the bar 66. A pin 70 is secured to and extended from the rear member 10', and is so positioned as to engage the upper extremity of the bar 66, so as to permit the said bar 66 to be set in predetermined initial position.

A plunger 71 is slidably mounted in a bracket 72 secured to the rear member 10', and is provided with an enlarged head 73 held in frictional engagement with the bar 66 by an expansion spring 74 co-axial on the plunger 71.

The latter described construction is such as will permit the plunger to frictionally hold the bar in any position.

A catch member 75 is secured to and extended from the bar 66, and has pivotally attached thereto as at 77 at its extended extremity a latch 76. A pin 78 is secured to and extended from the catch member 75, as a means of preventing outward displacement of the latch 76.

The above described construction is such as will downwardly advance the latch 76 when the pockets 58 are closed by the persons who deposit calling cards therein. The total amount of the said advancement is such as will permit the latch 76 to engage the hook member 79 secured to and extended from the locking bar 31, so as to prevent theft of the calling cards placed in the said pockets. A suitable marker 80 having affixed thereto any suitable instructions relative to the effect that the device is full, is secured to the latch member 75, and it is visible through the opening 81 when the latch member is in a locked position.

A card holder 54 of box-like construction is secured to one side of the receptacle 10. This card holder 54 has formed therein at the front thereof an opening 56', so as to permit calling cards to be readily placed therein and removed therefrom in event the person calling has not the necessary card to affix his name and any other desired message to.

It is also understood that the above mentioned and described lock 61 may be omitted. This construction will permit our improved device to be used for the purpose of a depository for messages between one person and another as is often desirable and advantageous in business routine.

Having thus described our invention, what

we claim as new, and desire to protect by Letters Patent of the United States is as follows:—

1. In a device of the class described a lever pivotally attached intermediately to a door, said lever provided with a free extremity positioned in a coin guide, said coin guide secured to the said door, a locking pin pivotally attached to a support, said support pivotally attached intermediately to the said lever, the said locking pin adapted to normally engage in a notch formed in a locking bar slidably mounted in a bracket secured to the said door and in the said coin guide, and a means for manually operating the locking bar from the outside of the said door.
2. In a device of the class described a lever pivotally attached intermediately to a door, said lever provided with a free extremity positioned in a coin guide, said coin guide secured to the said door, a locking pin pivotally attached to a support, said support pivotally attached intermediately to the said lever, the said locking pin adapted to normally engage in a notch formed in a locking bar slidably mounted in a bracket secured to the said door and in the said coin guide, said locking bar formed with gear teeth, a pinion rotatively mounted on a bracket secured to the said door, meshing with said gear teeth, a knob positioned outside of the said door secured to a pin rotatively mounted in said door, said pin secured to said pinion.
3. In a device of the class described a lever pivotally attached intermediately to a door, said lever provided with a free extremity positioned in a coin guide, said coin guide secured to the said door, a locking pin pivotally attached to a support, said support pivotally attached intermediately to the said lever, the said locking pin adapted to normally engage in a notch formed in a locking bar slidably mounted in a bracket secured to the said door and in the said coin guide.
4. In combination with a device of the class described a lever pivotally attached intermediately to a door, said lever provided with a free extremity positioned in a coin guide, said coin guide secured to the said door, a locking pin pivotally attached to a support, said support pivotally attached intermediately to the said lever, the said locking pin adapted to normally engage in a notch formed in a locking bar slidably mounted in a bracket secured to the said door and in the said coin guide.

In testimony whereof we have affixed our signatures.
